DESIGN FOR A PYROPHORIC LIGHTER

Louis V. Aronson, Newark, N. J., assignor to Art Metal Works, Inc., a corporation of New Jersey

Application August 2, 1935, Serial No. 57,914

Term of patent 7 years

To all whom it may concern:

Be it known that I, Louis V. Aronson, a citizen of the United States, residing at Newark, in the county of Essex and State of New Jersey, have invented a new, original, and ornamental Design for a Pyrophoric Lighter, of which the following is a specification, reference being had to the accompanying drawing, forming part thereof wherein:

Figure 1 is a plan view of the pyrophoric lighter showing my new design;

Fig. 2 is a front elevational view of the pyrophoric lighter; and

Fig. 3 is a side elevational view of said pyrophoric lighter.

I claim:

The ornamental design for a pyrophoric lighter, substantially as shown.

LOUIS V. ARONSON.
